UNITED STATES PATENT OFFICE.

FREDERICK JAMES SCHENK, OF MONTICELLO, ILLINOIS.

HARNESS.

SPECIFICATION forming part of Letters Patent No. 692,716, dated February 4, 1902.

Application filed May 4, 1901. Serial No. 58,754. (No model.)

To all whom it may concern:

Be it known that I, FREDERICK JAMES SCHENK, a citizen of the United States, residing at Monticello, in the county of Piatt and State of Illinois, have invented certain new and useful Improvements in Harness; and I do hereby declare the following to be a full, clear, and exact description of the invention, such as will enable others skilled in the art to 10 which it appertains to make and use the same.

My invention relates to harness construction, and while my invention will be found desirable and applicable for use in operatively connecting various portions of the harness together yet I will for convenience in illustrating my invention as applied to use 15 show the same as employed to form a bridle.

The object of my invention is to provide 20 securing devices which are especially designed for forming bridles or other parts of the harness out of woven fabric, as cords or small ropes, and while I shall confine my 25 specification as above set forth it will be obvious that other uses than those specified may be made of my securing devices.

In the accompanying drawings, Figure 1 30 illustrates my invention as applied to use upon a bridle, showing the same in its operative condition. Fig. 2 illustrates the means which is employed in uniting two ends of straps together and extending them in different directions.

In order to conveniently designate the several parts of my invention and the co-operating accessories, numerals will be employed, 35 of which 1 illustrates the bit of a bridle of the usual or any preferred construction, to which I connect the headstall proper, 2, formed, preferably, of a section of a rope by means of 40 the tubular socket 3. The checkreins 7 may also be connected directly to the ring of the bit 1 by a similar socket 8, the checkreins preferably being disposed upward between the ears of the animal and connected together 45 by the device designated by the numeral 8. In order to prevent the rope from casually slipping when thus disposed in the tubular section 12, an anchoring-point 14 may be formed upon the interior wall of the device, 50 preferably in the central part of the cut-away section or opening 13, as more clearly illustrated in Fig. 2. The anchoring-point will

therefore take into a contiguous part of the rope or its equivalent, and thus insure against casual slipping of the device until the rope 55 is grasped and drawn away from said point, when said device may be readjusted as desired.

In Fig. 2 I have illustrated a tubular socket 19 as being connected to the body portion or 60 main section 20, the parts 20 corresponding to the parts 12 in Fig. 2 and the part 15 being replaced by said section 19. By this arrangement I am enabled to connect a branch of the rope, as indicated by the numeral 21, to 65 the main section, the end of said branch being entered in the tubular socket 19 and secured by the rivet 22.

The entire device illustrated in Fig. 2 is indicated in Fig. 1 by the numeral 26. 70

If desired, the upper portion of the headstall may consist of the section of strap, as indicated by the numeral 29, and the rope 30, passing over said strap, may be anchored or stayed in position by the device indicated by 75 the numeral 31.

While I have described the preferred construction and combination of parts deemed necessary in materializing my invention, I desire to comprehend in this application all 80 such substantial equivalents and substitutes as may be considered to fairly fall within the scope of my invention.

Believing that the construction and manner of using my improved anchoring devices 85 have been made fully apparent from the foregoing specification considered in connection with the accompanying drawings, further description is deemed unnecessary.

What I claim as new, and desire to secure 90 by Letters Patent, is—

1. In harness construction, the herein-described attaching device comprising a tubular portion with cut-away portion intermediate its ends and a tubular socket rigid with 95 the tubular portion, substantially as described.

2. In harness construction, the herein-described attaching device comprising a tubular portion with cut-away portion intermediate its ends and a tubular socket rigid with the tubular portion and parallel therewith and closed at one end substantially as described. 100

3. In harness construction, the herein-described attaching device comprising a tubular portion with cut-away portion intermediate its ends and a tubular socket rigid with the tubular portion and parallel therewith and closed at one end, and an anchoring device extending laterally from the uncut vertical wall of the body portion to engage the

portion of a rope disposed opposite said cut-away portion. 10

In testimony whereof I affix my signature in presence of two witnesses.

FREDERICK JAMES SCHENK.
